United States Patent

Des. 241,588
Patented Sept. 28, 1976

241,588

SEAT

Stapleton Long, Morristown, Tenn., assignor to The
Berkline Corporation, Morristown, Tenn.

Filed Aug. 26, 1975, Ser. No. 607,920

Term of patent 7 years

Int. Cl. D6—01

U.S. Cl. D6—37

FIG. 1.

FIG. 2.

FIG. 3.

FIG. 4.

FIG. 5

FIG. 6

FIG. 7.

FIG. 8.

FIG. 9

FIG. 1 is a front perspective view of a seat in the form of a high-back chair showing my new design;

FIG. 2 is a side perspective view thereof;

FIG. 3 is a front perspective view of the seat in the form of a sofa showing my new design;

FIG. 4 is a side perspective view of the sofa of FIG. 3;

FIG. 5 is a side perspective view of the seat in the form of a low-back chair showing my new design;

FIG. 6 is a front perspective view of the chair of FIG. 5;

FIG. 7 is a top perspective view of the high-back chair of FIGS. 1 and 2;

FIG. 8 is a top perspective view of the sofa of FIGS. 3 and 4; and

FIG. 9 is a top perspective view of the low-back chair of FIGS. 5 and 6.

The side not shown is like the side shown while the rear of the seat is plain and unornamented.

I claim:

The ornamental design for a seat, as shown and described.
